Application August 24, 1954, Serial No. 31,985

Term of patent 3½ years

(Cl. D48—20)

To all whom it may concern:

Be it known that I, Ludwig Eickemeyer, a citizen of the United States, residing at Union, in the county of Union and State of New Jersey, have invented a new, original, and ornamental Design for a Combined Lamp and Clock, of which the following is a specification, reference being had to the accompanying drawing, forming a part thereof.

Fig. 1 is a front elevational view of a combined lamp and clock, showing my new design.

Fig. 2 is a side elevational view thereof.

The dominant features of the design reside in the portions shown in full lines.

I claim:

The ornamental design for a combined lamp and clock, substantially as shown and described.
